UNITED STATES PATENT OFFICE.

JOHN D. A. JOHNSON, OF OMAHA, NEBRASKA.

MECHANICAL MOVEMENT.

No. 843,823.

Specification of Letters Patent.

Patented Feb. 12, 1907.

Application filed September 28, 1906. Serial No. 336,610.

To all whom it may concern:

Be it known that I, JOHN D. A. JOHNSON, a citizen of the United States, residing at Omaha, in the county of Douglas and State of Nebraska, have invented certain new and useful Improvements in Mechanical Movements, of which the following is a specification.

This invention relates to improvements in mechanical movements of the class adapted for use for washing-machines, churns, and other like machines where a reciprocatory rotary motion is desired for the dasher or agitator, the latter being positioned in the tub or receptacle for moving the contents in a circular and then a reverse direction. The invention is illustrated in connection with a washing-machine.

The principal object of the invention is to present a mechanical movement which is actuated by a lever moved forward and backward in a manner to cause rotation of a balance-wheel in a continuous direction and to cause a reciprocatory movement of the operating or vertical shaft.

Another object is the employment of a balance-wheel which will operate in a position closely adjacent to the cover of a washing-machine, said balance-wheel to have a movement practically free from vibration and which will supply a sufficient momentum to assist in the movement of the lever.

The invention also has reference to certain features of construction of a frame made necessary for containing the devices shown and to the presentation of a slotted rack-bar considered new in connection with the lug-bearing gear used therewith and to certain guide and yoke construction found convenient.

With these and other objects in view the invention presents a novel construction and arrangement of parts, as shown herein and in the appended claims, and as illustrated by the drawings, wherein—

Figure 1 represents a vertical section of the invention, shown operatively mounted upon a washing-machine tub, the figure being sectioned centrally to disclose the mechanism. Fig. 2 is a detail relating to Fig. 1, partly in section, being a plan view of the rack-bar and showing the pinion of the balance-wheel and base of the annular yoke in section, being a view sectioned on the line *a b* of Fig. 1. Fig. 3 is a broken-away figure, being a detail re-

lating to Fig. 1, partly in section, to more clearly show certain parts. Fig. 4 is a plan view of the bottom of the rack-bar, gear-wheel 29, and yoke 18. Fig. 5 is a perspective view of sleeve 13 and engaging plate. Fig. 6 is a side view of the inclosing cap and yoke 18 looking across the center of cover 4 to lever 35. Fig. 7 is a sectional view of the inclosing cap, as on line *c c* of Fig. 9. Fig. 8 is a broken-away view, being a perspective presentation of a part of the rack-bar to clearly show the yoke 18. Fig. 9 is a plan view of the frame and showing a part of the rack-bar. Fig. 10 is a detail relating to Fig. 1, partly in section, to show relative position of parts.

Referring to the figures in the drawings, the numeral 1 represents the wall of a tub, 2 the legs, 3 the leg-braces, 4 the tub-cover and 5 the wringer-stand of a washing-machine, the legs being extended to form ribs of the tub. These parts are old and common to washing-machines. The devices employed by me are supported by the cover and will now be explained.

I employ a vertical shaft 6, which extends downward within the tub a short distance below cover 4, where by means of key 7 it is secured upon disk-rod 8, the latter passing downward on a line with said shaft, provided with fins 9 and having an enlarged free end 10. The disk 11, having a series of prongs 12, projecting downwardly and outwardly, is adapted to have a sliding vertical movement upon disk-rod 8. This upward sliding movement of disk 11 is limited by the ring or washer 11, seated on the disk-rod. The prongs 12 are depended upon to engage clothing or other articles to be laundered, while the vertical shaft has its reciprocatory rotary movement, so that a thorough turning or agitation of these articles may be made during the process of laundering. The use of the disk and prongs for this purpose is old in the art.

I employ a sleeve 13, Fig. 5, which vertically traverses cover 4, having the engaging plate 14 formed transversely upon its upper end. Plate 14 has bolt-apertures 15 and raised bracket ends 16, these apertures corresponding to the apertures 17 of the yoke 18, Fig. 8. The ends of yoke 18 are seated within the brackets 16 of plate 14 and secured to cover 4 by means of bolts 19, Fig. 10, passing therethrough. This is considered

a good construction as a holding means, since the yoke by this arrangement may be and preferably is cast integral with the inclosing cap 20, which extends from the yoke 5 to the edge of cover 4, and thereby the entire frame may be cast in one piece.

I employ the horizontally-disposed balance-wheel 21, having a pinion 26, preferably formed integral thereon, and extended 10 downward transversely from the plane of the wheel adjacent to the upper face of yoke 18, and provide the annular groove 22 upon the end of this pinion and seat therein and upon yoke 18 the series of balls 23.

15 Transversely and rigidly secured upon shaft 6 is pinion 24, which has engagement within the horizontally-disposed rack-bar 25. Upon the outer end of pinion 26 and encircling the vertical shaft is a washer 27, 20 and extending through this shaft at its upper end upon the outer face of the washer is key 28. The vertical shaft furnishes a pivotal mounting for balance-wheel 21 and its pinion 26, the weight of this wheel and pinion resting upon the balls 23 and yoke 18. Yoke 18, 25 as clearly shown by Fig. 10, is supported upon the plate 14, and does not make contact with pinion 24. The vertical shaft therefore is not impeded with the weight of 30 these parts and is free to receive actuation by any force brought to bear upon its pinion 24.

The wall of inclosing cap 20, (best shown by Figs. 1 and 9,) may be formed of any 35 fanciful cen work or grille-work, as represented by Fig. 1, or may have a plain outer wall, as shown by Fig. 9, without changing the form or functions. One of the functions of inclosing cap 20 is to furnish a pivotal 40 mounting, as at 55, for gear-wheel 29, as clearly shown by Figs. 1 and 7, and therefore may be considered a yoke. Another function is to inclose gear-wheel 29, which otherwise would be exposed, and, as already stated, 45 the inclosing cap is the principal part of the frame.

The inclosing cap comprises an upper circular horizontally-disposed wall 30, Fig. 7, preferably apertured at its center to furnish 50 a pivotal mounting 55 for gear-wheel 29 and formed with a substantially vertical side wall 31, which terminates in an annular base 32. Base 32 and wall 31 are formed with extensions which are opposite each other, one of 55 these extensions being the yoke 18, the other being the curved arm 33 passing downward below the plane of cover 4 to furnish a pivotal mounting at 34 for lever 35. Lever 35 has formed on its outer end the socket 36, 60 adapted to seat therein a handle 37.

Upon lever 35 at 38 is pivotally mounted rack-bar 25. This rack bar consists of side arms 39 and 40, held adjacent and parallel by the end pieces 41 and 42, and is continued 65 outwardly from end piece 42 as a rod 43 to

the mounting thereof at 38 upon lever 35. End piece 42 is provided with a slot or aperture 44, Fig. 2, having parallel inner side walls 45 and 46, which are transversely disposed with reference to arms 39 and 40 and 70 is provided with ends having lengthwise curved inner walls 47 and 48.

The horizontal plane occupied by the rack-bar is above base 32 and below gear-wheel 29 and is upon the same plane as pinion 24, and 75 said rack-bar horizontally traverses inclosing cap 20, the rod 43 of the rack-bar resting in aperture 49, arms 39 and 40 pass beneath the yoke 18, and the inner edges 50, Fig. 6, of the yoke operate as guides for these arms. Near 80 the periphery of gear-wheel 20 is rigidly mounted the wrist-pin 51, upon which is seated the roller 52, Figs. 1-7, adapted to have a seating within slot 44.

From the description it will be understood 85 that lever 35 may be moved backward and forward in directions away from or toward the vertical shaft, and such movement will cause a corresponding rotation of pinion 24, which movement will be communicated to 90 the vertical shaft, and in operation lever 35 is moved forward and then backward, so that disk 11 and the prongs thereon will turn the contents of the tub with a horizontal swing, first in one direction and then in a reverse 95 direction. During this movement the teeth of the rack-bar are kept in contact with the teeth of the pinion of the vertical shaft by means of walls 50 of yoke 18. Rod 43 will have a slight vertical swing; but aperture 49 100 in the inclosing cap is provided of a sufficient extent, so that there will be no contact to produce friction.

Arms 39 and 40 of the rack-bar slide upon projections 53, Fig. 10, thereby reducing the 105 surface contact of these arms during this movement, and the slight vertical swinging movement of these arms is provided for by an adequate height of yoke 18.

The roller 52 is within slot 44 at all times, 110 and as the rack-bar moves toward the vertical shaft the roller is pressed against the wall 45 of the slot, as is evident, and wheel 29 made to rotate. The teeth of wheel 29 make contact with the teeth of the pinion 115 upon the balance-wheel, causing the latter to rotate. When the inward stroke of lever 35 is completed, roller 52 at that time reaches the center, longitudinally considered, of the slot, the momentum of balance-wheel 21 120 carrying wheel 29 past a dead-center, and when lever 35 is moved outwardly from the vertical shaft roller 52 commences to have a pressure upon wall 46 of the slot and gradually approaches the opposite end of said slot. 125 Wheel 29 therefore has a continuous movement in one direction during operation. When the rack-bar is drawn outward, the roller will pass endwise of the slot again, but in a reverse direction. The roller travels from one 130

end of the slot to the opposite end, its function being simply to connect gear-wheel 29 with the rack-bar, and as is obvious the roller travels the entire surfaces of walls 45 and 46 of the slot for each revolution of wheel 29. Lever 35 causes rotation of gear-wheel 29 and pinion 24 by the forward and backward movement of the rack-bar, since the latter carries the roller along within its slot and at the same time actuates pinion 24.

It is considered that the balance-wheel is situated in a position of advantage, since the center of gravity of all metal parts is very closely at the center of cover 4. The inclosing cap 20 is cut away at 54 to allow operative contact between pinion 26 of the balance-wheel and gear-wheel 29.

It will be noted that pinion 26 has an adequate length, and thereby furnishes an extensive vertical seating for balance-wheel 21, and thereby operates in a manner to lessen vibration. This is considered of importance, since the balance-wheel has a considerable speed and would vibrate and have an uneven movement unless a long vertical seating was provided. In the present construction the balance-wheel rotates swiftly, noiselessly, and without any uneven movement.

It will be noted that the operation of reciprocal rotation of the vertical shaft is accomplished regardless of the direction of rotation of the balance-wheel or gear-wheel 29, the movement of these wheels being wholly independent of that of the vertical shaft.

Having described the parts, any further statements as to operation is not considered necessary. It will be remembered, however, that the balance-wheel is useful for furnishing momentum for carrying the movement of prongs 12 when the latter engage the clothing, and, as already stated, preventing the dead-center of gear-wheel 29. This momentum also assists a continued movement of the rack-bar.

What I claim as my invention is—

1. A mechanical movement as described, comprising a vertical shaft, a pinion rigidly mounted thereon between its ends; a horizontally-disposed rack-bar mounted engagingly with the rigidly-mounted pinion of the vertical shaft and having a horizontally-extending oval trackway formed transversely upon one of its ends; a pinion seated pivotally upon said vertical shaft and having a part of its periphery extended to form a balance-wheel; a horizontally-disposed rotatable annular gear engaging the pivotally-seated pinion on said vertical shaft and having an arm thereon transversely formed and extended to a seating within the oval trackway formed upon the end of the rack-bar; and means to cause a lengthwise movement of the rack-bar.

2. A mechanical movement as described,

comprising a vertical shaft, a pinion rigidly mounted thereon between its ends; a horizontally-disposed rack-bar mounted engagingly with the rigidly-mounted pinion of the vertical shaft and having a horizontally-extending double-faced trackway formed transversely upon one of its ends; a pinion seated pivotally on said vertical shaft and having a part of its periphery horizontally extended to form a balance-wheel; a horizontally-disposed rotatable annular gear engaging the pivotally-seated pinion on said vertical shaft and having an arm thereon transversely formed and extended to a seating within the double-faced trackway formed upon the end of the rack-bar; and means to cause a lengthwise movement of the rack-bar.

3. In a mechanical movement, the combination of a vertical shaft, a yoke, a horizontally-disposed rack-bar, a pinion rigidly mounted upon said vertical shaft; said yoke having a transverse seating upon said vertical shaft and having adjacent and downwardly-extending arms passing rigidly-mounted pinion, to form guides; said horizontally-disposed rack-bar being formed with a parallel and adjacently-extending guide-arm thereon and with a base portion thereon having a transversely-formed slot therein, said rack-bar and connected guide-arm being seated between said downwardly-extending arms of said yoke; a pinion seated pivotally upon said vertical shaft and having a part of its periphery extended horizontally to form a balance-wheel; a horizontally-disposed rotatable annular gear engaging the pivotally-seated pinion upon the vertical shaft and having an arm thereon transversely formed and extended to a seating within said transversely-formed slot of the base portion of said rack-bar; and means to cause a lengthwise movement of said rack-bar.

4. In a mechanical movement, the combination of a vertical shaft, a yoke, a horizontally-disposed rack-bar, a series of balls, a pinion rigidly mounted upon said vertical shaft; said yoke having a transverse seating upon said vertical shaft and having adjacent and downwardly-extending arms passing rigidly-mounted pinion, to form guides; said horizontally-disposed rack-bar being formed with a parallel and adjacently-extending guide-arm thereon, and with a base portion thereon having a transversely formed slot therein, said rack-bar and connected guide-arm being seated between said downwardly-extending arms of said yoke; a pinion seated pivotally upon said vertical shaft, formed with an annular groove upon its lower end and having a part of its periphery extended horizontally to form a balance-wheel; a horizontally-disposed rotatable annular gear engaging the pivotally-seated pinion upon the vertical shaft and having an arm.

thereon transversely formed and extended to a seating within said transversely-formed slot of the base portion of said rack-bar; said series of balls being seated upon said yoke and in the annular groove of said pivotally-seated pinon; and means to cause a lengthwise movement of said rack-bar.

In testimony whereof he has affixed his signature in presence of two witnesses.

JOHN D. A. JOHNSON.
